UNITED STATES PATENT OFFICE.

JOSEF KNOPS, OF AIX-LA-CHAPELLE, GERMANY.

SHOE-SPILE RASP.

SPECIFICATION forming part of Letters Patent No. 781,006, dated January 31, 1905.

Application filed August 25, 1903. Serial No. 170,698.

To all whom it may concern:

Be it known that I, JOSEF KNOPS, a citizen of the German Empire, residing at Aix-la-Chapelle, Germany, have invented an Improved Shoe-Spile Rasp, of which the following is a specification.

My present invention relates to an improved shoe-spile rasp, and has for its object to provide an adjustable spile-rasp the handle of which can be displaced in respect of the special rasping-plate, so that instead of two rasps of different shapes used hitherto the improved rasp can be used for all purposes. One of the rasps used hitherto has an oblique shaft and is designed for rasping the spiles in the sole, especially in the foremost part of the latter, while the other rasp, having a straight vertical shaft and provided with a circular rasping-plate, is designed for rasping the spiles above the heel.

The rasping-plate of the improved spile-rasp can, if worn out, easily be replaced.

The shoe-spile rasp is illustrated in the accompanying drawings, in which—

Figure 1 is a side elevation of the shoe-spile rasp. Fig. 2 is the front view of the same. Fig. 3 is a perspective view of the same. Fig. 4 is the top view of the rasp; and, finally, Fig. 5 is the top view of the special rasping-plate separately.

Similar characters refer to similar parts throughout the several views.

The under end 2 of the shaft 1 of the spile-rasp is flattened, and its undermost part is bifurcated to form two eyes 3. The flattened shaft 2 is provided with a slit 4. By means of a screw-bolt 5 the shaft is pivotally fastened to the eyes 6 of the quadrangular frame 7, loosely arranged upon the rasping-plate 8. In the middle of this plate there is integrally connected to the said plate an eye 9. The above-named screw-bolt 5 penetrates the eyes 6 of the frame 7, as well as the eyes 3 of the shaft 1 and the eye 9 of the plate 8, thus connecting the shaft 1 to the frame 7 and both to the plate 8.

Through the slit 4 of the flattened end 2 of the shaft 1 is guided a bow 10, made of a strip of thin sheet metal and provided all along with a longitudinal slot 11. The bow 10 is secured by rivets 12 to the side faces of the frame 7, and its ends are fastened, by means of small screws 13, to the body of the rasping-plate 8. Through the same slit 4 of the shaft 1 penetrates an arc-shaped plate 14, arranged over the bow 10 and provided with a pole on each side of the shaft 1. Through the slot 11 of the bow 10 and through the holes of the plate 14 penetrate the screws 15, pressing, when their nuts 16 are screwed on, the bow 10 and the adjusting-plate 14 tightly together, securing the shaft 1 in such a way in a certain position. In order to rasp the spiles penetrating the sole, especially its foremost part, I secure the articulated shaft 1, by means of the adjusting-plate 14 and the screws 15, in an oblique position, as shown in Fig. 3; but for rasping the spiles above the heel I secure the shaft 1 to the plate 8 in a straight direction, as represented in Fig. 1. I prefer to make the heads of the screws 15 quadrangular in shape, which, leaning against the flat side surfaces of the shaft 1, prevent the screw-bolts from rotating and being loosened.

The quadrangular frame 7, leaning against the upper surface of the rasping-plate 8, is destined to transfer the power executed on the shaft 1 unto the rasping-plate and makes the whole instrument a solid one that offers sufficient resistance to the pressure of the workman. When the rasping-plate 8 is worn out, I loosen the screws 13, as well as the bolt 5, and can hereafter replace the plate by another.

Having now particularly described and ascertained the nature of my invention and in what manner the same is to be performed, I declare that what I claim is—

An adjustable shoe-spile rasp having in combination a rasping-plate, a shaft pivotally secured to said rasping-plate and provided with a slit, a frame pivotally connected with

said shaft and loosely arranged upon said rasping-plate, a slotted bow passing through the slit of said shaft and having its ends removably attached to said rasping-plate and permanently secured to said frame, an adjustable bow-shaped plate passing through the slit of said shaft in juxtaposition to said slotted bow, and means for securing said shaft at any suit-

able angle to said rasping-plate, substantially as set forth. 10

In witness whereof I have hereunto set my hand in presence of two witnesses.

JOSEF KNOPS.
